UNITED STATES PATENT OFFICE.

CONSTANTINE LEE STRAUB, OF MILWAUKEE, WISCONSIN, ASSIGNOR TO POWER AND MINING MACHINERY COMPANY, OF NEW YORK, N. Y., A CORPORATION OF NEW JERSEY.

GAS-PRODUCER.

No. 909,345.

Specification of Letters Patent.

Patented Jan. 12, 1909.

Application filed April 7, 1906. Serial No. 310,493.

To all whom it may concern:

Be it known that I, CONSTANTINE LEE STRAUB, citizen of the United States, residing at Milwaukee, in the county of Milwaukee and State of Wisconsin, have invented certain new and useful Improvements in Gas-Producers, of which the following is a specification, reference being had therein to the accompanying drawing.

This invention relates to improvements in gas producers of the class in which use is made of a fuel holding and gas generating chamber in combination with a steam generator and means for moving air and steam and delivering them to the lower part of the fire bed. The apparatus, as an entirety, is generally used in direct connection with a gas engine, under such relationship of parts that the suction of the engine is exerted directly upon the gas generating chamber, drawing the gas therefrom and also drawing thereto the supplies of air and steam.

Figure 1 is a central vertical section of a gas producer embodying my improvements. Fig. 2 is a plan view, the upper part of the fuel magazine being removed. Fig. 3 shows the furnace shell or casing in section, and also shows the grate supporting plate in plan view and the superheater chambers thereon. Fig. 4 is a plan view of the annular plate in which is supported the grate, the preferred construction of the latter being also represented. Fig. 5 is a cross sectional view taken on the line x, x of Fig. 4. Figs. 6 and 7 are detail views illustrating the grate sections.

In the construction shown there is an exterior casing or shell 1 which extends from the bottom of the apparatus to the cover parts at the upper end, this shell being formed in two or more sections of sheet metal. It incloses the ash chamber 2, the lower part of the fire chamber 3 and the upper part of the fire chamber or furnace 4. Within the latter there is a lining 5 of suitable refractory material, and between this and the shell there is brickwork or suitable packing 6.

7 indicates the grate, the bars of which are supported upon the annular plate 8 which also carries the superheating chambers 9. Between the latter and the lining 5 is the ring plate 10. The plate 8 furnishes the support for nearly all of the internal parts and is strongly secured in place by means of the bracket plates 11 riveted to the outer casing

or shell 1. At the bottom the casing is secured to the floor plate 12 upon the top of which there is a bed of refractory material, firebrick or the like, as at 13. The grate bars 14 are each pivoted at its ends at 15 in sockets formed in the supporting plate 8. One of the bars 14 has a depending arm 16 which is loosely connected to a rocker arm 17 carried by rock shaft 18. The latter is supported in a bracket or hanger 19 at its inner end, and at its outer end extends through the shell or casing 1 and is provided with a handle 20 on the outside of the furnace. Each of the grate bars has a short projecting arm 21 and these are joined together by a connecting bar 22. When the lever 20 is moved back and forth it, through the parts described, causes the rocking of the grate bars 14.

It will be observed by reference to Figs. 3 and 4 that the opening in the plate 8 in which is situated the grate is of reduced or relatively small size, as compared with the plate itself, and that the grate is approximately circular in outline, and composed of a series of movable grate bars the central one or ones of which are approximately rectangular in outline while the outside bars are approximately of segmental shape.

The preferred form of grate is indicated in Figs. 4, 5, 6 and 7. As here represented each bar is made up of a plurality of parts comprising a shaft 14^a, preferably rectangular in cross section, and a series of removable fuel supporting sections supported upon the said shaft. As shown in Fig. 4 the grate is formed of three bars, the central one of which is substantially rectangular in outline, and is formed of a series of separate sections 14^b, Fig. 7, supported side by side upon the central shaft 14^a. Each section 14^b is formed with a pair of downwardly extending parts arranged to constitute a seat 14^c for the supporting shaft or bar 14^a. The upper surface of each of these sections is rounded as indicated in Figs. 5 and 7, and each is provided with a spacing flange 14^d. The outside grate bars, which are of segmental shape in outline, are each composed of a series of grate parts 14^b set upon the central part of a shaft 14^a, and two grate parts 14^d, shaped as represented in Fig. 6, one at each end of the shaft.

At the top of the refractory lining wall 5 there is an inwardly projecting flange formed

of similar material. The body part is shown at 23 and the inwardly projecting or overhanging part at 24. At 25 it is beveled or chamfered for a purpose to be described. At 5 intervals the inwardly extending part 24 is provided with recesses or vertically open spaces 26 to permit the insertion downward of bars as will be described.

The coal feeder or magazine has the upper 10 part 27 and the lower part 28. The latter consists of the sheet steel tube extending downward to lines well below the horizontal planes of the region where the gas travels outward from the center. Around this 15 downwardly extending part of the fuel magazine is arranged the steam generator 29. It has the vertical leg part 30 and the horizontal pan-like part 31. Its walls are formed of sheet steel comprising the cylindrical 20 portion 32 parallel to the steel tube 28, and the upper part 33 riveted thereto.

34 is a horizontal sheet steel diaphragm forming the top of the boiler or evaporator. At its edges it is secured by a steam tight joint 25 to the upwardly turned edges of the upper part 33 of the bottom of the boiler, and the two together are supported upon and firmly fastened to the bracket ring 35 which at 36 is riveted to the upper edge of the shell or casting, 1. The top of the furnace is shown at 37. It has a laterally extended floor capable of furnishing support when the fuel is to be introduced and also when the material in the furnace is to be "barred" or when for other 30 purposes operatives require such support. This top part 37 is a casting shaped to have a supporting ring flange 38 resting upon and secured to the bracket flange 35 and having a central tubular part 39 to receive the upper 35 part 27 of the fuel magazine and to support the lower portion 28 thereof. It is connected to the latter by a bracket, flange or ring 40 which lies under the sheet steel diaphragm 34, and to which the tubular part 28 40 is riveted. The top 37 is also formed with a series of cavities to permit the employment of small manholes 41, these being situated directly above the central vertical leg 30 of the boiler or evaporator to permit access to 45 the interior of the boiler for cleansing it whenever required. The top 37 is also formed with conical cavities 42 which extend down to the sheet steel diaphragm 34.

43 are hollow cones rigidly bolted to the 50 flanges at the inner walls of the cavities 42. They extend downward through the wall 33 of the boiler. In this way a passage is provided directly above each of the recesses at 55 in the top part 23 of the lining wall, 60 through which passages the operatives can insert bars to the fuel mass whenever desired. In each of these passages there is a cone plug 44 so shaped as to automatically tightly close the passage when the plug is in 65 place.

45, 45 are tubes extending from the upper part of the chamber in the exaparator or boiler to the superheaters 9. They are situated in the interior of the mass of lining materials 5 and 6. Preferably there is one of 70 these for each of the superheaters 9. They conduct the steam and air either or both from the boiler to their respective superheaters. The steam and air are compelled to travel nearly half way around the furnace 75 in the superheater and finally escape from the latter through the passage 46 into the ash pit 2 or chamber below the fire grate 7.

Water is supplied to the evaporator or boiler 29 through the pipe 47, the end 48 of 80 which is placed somewhat above the wall 33 of the boiler. The flow of water is controlled by a float valve mechanism 56 suitably arranged which insures that the water shall rise in the boiler only to a predetermined 85 level which is always below the upper end of the steam and air pipe 45.

57 indicates an overflow pipe leading from the evaporating pan so that should the float valve mechanism or other water-control device become deranged or fail to preserve the proper water level, there will be no chance of the pan becoming too full and water flowing into the steam pipes that connect with the base of the producer. 95

Air is admitted to the boiler through one or more pipes 49, the entrance to each of which can be opened, closed or graduated as desired by the valve at 50 having the handle 51. In addition to this means of supplying 100 air there is a pipe 52 which communicates with the chamber below the grate and is adapted to take in air at some suitable point outside the producer. This pipe is controlled by a valve or damper 53. 105

54 is a hand fan or blower adapted to force air through the duct 52.

The mode of operation of the apparatus described will be readily understood by those acquainted with the art. The coal or fuel is 110 introduced to the heating and gas producing chamber 3, 4, above the grate bars, and after the producing of the gas has been commenced it can be continued indefinitely, the fuel being fed at suitably frequent intervals to 115 the magazine and feeder 27—28, from which it can descend under substantially constant pressure.

The operation of the producer is started at the time of commencing the firing by 120 forcing air into the chamber 2 and up through the grate by means of the blower at 54. And thereafter, as occasion requires, some of the air for the furnace may be taken through the pipe 52, the amount being subject to control by the valve or damper 53.

Water in controlled quantities is admitted through the pipe 47 to the evaporator or boiler and when sufficient heat is withdrawn from the rising gas steam is formed which is 130

conducted by the pipes 45 downward to the superheaters 9. Air, through the valves at 50, is admitted in quantities graduated as desired to the interior of the evaporator or 5 boiler, and thence it passes with the steam down the pipes 45 to the generator and the lower part of the fire bed.

The gas generated in the fuel heating chamber rises to the top and is by the inwardly turned portion 24 of the lining or brickwork directed inward to come in close proximity with the vertical leg of the evaporator and then pass over the beveled or chamfered part 25 and is caused to travel 15 close to the under surface of the horizontal evaporator, and is finally guided through and taken off through the exhaust pipe, at 55.

What I claim is:

1. In a gas producer, the combination 20 with the furnace having the fuel heating chamber and the evaporator or boiler above said chamber, of the inner lining of refractory material for said chamber having a wider lower part, and the narrower upper 25 part projected inwardly toward the center, said inwardly projecting part lying in horizontal planes above the lower end of the evaporator or boiler, substantially as set forth.
2. In a gas producer, the combination 30 with the furnace part having a fuel heating chamber, of an evaporator or boiler above the said chamber, an inner lining of refractory material for the fuel heating chamber 35 having its upper portion extended inward toward the center at horizontal planes above the bottom of the boiler, and tubes inserted between the lining and the shell of the fur-

nace leading downward for taking steam from the boiler to the lower part of the fire 40 body, substantially as set forth.

3. The combination with the gas producing chamber having an interior lining of refractory material the upper part of which projects inwardly beyond the lower part, the 45 fuel magazine having the central sheet metal tube 28 extended down to points below the upper part of the refractory lining and serving as part of an evaporator or boiler, the sheet steel walls riveted to the said central 50 tube extending outward, the diaphragm or top wall 34 having its edges secured to the edges of the aforesaid sheet metal walls, and the ducts for conveying steam from the said boiler to the lower part of the fire bed, substantially as set forth.

4. In a gas producer, the combination with the furnace part having a fuel heating chamber, of an evaporator or boiler above the said chamber, a lining of refractory material for the fuel heating chamber having its upper portion extended inward toward the center on horizontal planes above the bottom of the boiler, and means arranged to cause a circulation of the hot gases from the 60 fuel body over the extended portion of the refractory lining and in proximity to the evaporator or boiler, substantially as set forth.

In testimony whereof I affix my signature, 70 in presence of two witnesses.

CONSTANTINE LEE STRAUB.
